(57) **CLAIM**

The ornamental design for a dish rack, as shown and described.

DESCRIPTION

FIG. 1 is a top perspective view of the dish rack showing my new design.

FIG. 2 is a top view thereof.

FIG. 3 is a bottom view thereof.

FIG. 4 is side view thereof.

FIG. 5 is another side view thereof.

FIG. 6 is front view thereof.

FIG. 7 is a back view thereof.

FIG. 8 is a bottom perspective view thereof; and,

FIG. 9 is another top perspective view thereof.

The broken lines showing other parts of the dish rack form no part of the claimed design.
